UNITED STATES PATENT OFFICE.

BENJAMIN P. MCKINLEY, OF MURRAY HILL-FLUSHING, NEW YORK, ASSIGNOR TO
HEMCO ELECTRIC MANUFACTURING COMPANY, INC., OF LONG ISLAND CITY, NEW
YORK, A CORPORATION OF NEW YORK.

DESIGN FOR A DIAL FOR RADIO RECEIVING APPARATUS.

Application filed September 6, 1924. Serial No. 10,693. Term of patent 14 years.

To all whom it may concern:

Be it known that I, BENJAMIN P. MCKINLEY, a citizen of the United States, residing at Murray Hill-Flushing, in the borough and county of Queens, city and State of New York, have invented a new, original, and ornamental Design for a Dial for Radio Receiving Apparatus, of which the following is a specification, reference being had to the accompanying drawing, forming a part thereof, in which—

Figure 1 is a perspective view looking at the front and side showing my new design; and Figure 2 is a side elevation of the dial.

I claim:

The ornamental design for a dial for radio receiving apparatus, as shown.

BENJAMIN P. MCKINLEY.
